UNITED STATES PATENT OFFICE.

HENRY L. LIGHTNER, OF SAN FRANCISCO, CALIFORNIA.

ROTATING GRAVITY-ENGINE.

SPECIFICATION forming part of Letters Patent No. 578,062, dated March 2, 1897.

Application filed July 20, 1896. Serial No. 599,870. (No model.)

To all whom it may concern:

Be it known that I, HENRY L. LIGHTNER, a citizen of the United States, residing in the city and county of San Francisco, State of California, have invented an Improvement 5 in Rotating Gravity-Engines; and I hereby declare the following to be a full, clear, and exact description of the same.

My invention relates to an improvement in 10 engines.

It consists of the parts and the constructions and combinations of parts hereinafter described and claimed.

Figure 1 is a side elevation of the engine. 15 Fig. 2 is an end elevation. Fig. 3 is a sectional detail of one of the slide-valves.

I have illustrated my invention by two cylinders A and B, standing at right angles with each other. These cylinders have a central 20 shaft or trunnions, to which they are secured so as to rotate upon this shaft.

In the present case I have shown the connection made by means of disks or collars C upon the exterior of the cylinders at a point 25 central between their ends, and these disks are bolted together, so as to retain the cylinders in their relative position, while not interrupting the clear passage from one end to the other of the cylinders.

30 The shafts D, which extend outwardly from these cylinders and disks, are journaled in suitable supports, so as to allow the cylinders sufficient space to swing freely. The shafts D are here shown as being made hollow, and 35 upon one side they are connected with an inlet-pipe E for the admission of steam or other medium under pressure, while at the other side is an exhaust-passage F, through which the steam is delivered after it has performed its office. From the hollow inlet 40 trunnion or shaft D pipes G extend to the opposite ends of the two cylinders A and B, and exhaust-pipes H in like manner lead to the hollow discharge-shaft D upon the opposite side.

45 Within the cylinders are fitted heavy weights I, which are adapted to slide smoothly from one end to the other of the cylinders as the latter are revolved. The cylinders rotate 50 within a circle or segment J, so disposed that at approximately the lowest point which the cylinders pass this segment is provided with

a flattened or differently-curved portion L, which acts upon the valve-stem K, so as to open an inlet-valve and allow the steam to pass 55 into the cylinder. This immediately forces the heavy weight or plunger I to the opposite and upper end of the cylinder. The arrangement of the valve-gear is such that this movement of the weight takes place just after 60 the cylinder has passed the vertical central line, and the weight, when thrown to the upper end, will thus be at a point beyond the central line upon the opposite side, so that it acts by gravitation to rotate the cylinder and 65 bring itself down again to the lowest position. The weight in the other cylinder is actuated in a like manner, and both weights are thus constantly thrown to the upper end of the cylinder as fast as they have arrived at the 70 lowest point by gravitation.

In order to allow the weights to move freely and also to discharge the steam or medium by the pressure of which they are forced to the upper end of the cylinder, I have shown a 75 contact-plate at L, against which the valve-stems K impinge when they arrive at that point and thus open the valves to allow the steam or other medium to escape when the ends of the cylinders have arrived at this 80 point. This leaves the cylinders free, so that the weights can be thrown up without any resistance within the cylinder.

It will be understood that the valves, which are indicated at K, may be actuated in various ways. They may be slide, rotary, or other forms of valve which are well known in mechanics.

The cylinders may be made of any desired length and diameter to provide for weights of 90 sufficient size, so that they will act by gravitation to continue the rotation of the apparatus, each weight being forced to the end cylinder which is uppermost as soon as the latter arrives in position to make the weight effective 95 so as to act by gravitation.

Having thus described my invention, what I claim as new, and desire to secure by Letters Patent, is—

1. An engine consisting of cylinders standing radially with relation to a journal-shaft to which they are centrally connected so as to revolve therewith, weights slideable from end to end of said cylinders, pipes connect-

ing the opposite ends of the cylinders with the hollow shafts or trunnions about which they are revoluble, and a supply-pipe connected with one end of the shaft, valves 5 whereby steam is admitted under pressure into the cylinders, an actuating device whereby the valves are opened when the ends of the cylinders successively pass the lowest point in their revolution, whereby the weights 10 are forced to the opposite and upper ends of the cylinders, exhaust-pipes connecting the ends of the cylinders with the shaft or trunnion opposite to the inlet-pipe for the escape of steam, and mechanism for opening the exhaust- 15 valves when they reach the upper part of their revolution, whereby the upper ends of the cylinders are opened to allow the escape of the steam and free movement of the weights in that direction.

20 2. An engine consisting of cylinders stand-

ing radially with relation to a journal-shaft to which they are centrally connected so as to revolve therewith, weights, forming pistons, slideable from end to end of said cylinders, pipes or passages connecting the opposite 25 ends of the cylinders with the hollow shafts or trunnions about which they are revoluble, a supply-pipe and an exhaust-pipe, and a circle or segment within which the cylinders rotate, having a flattened or differently-curved 30 portion at two opposite sides against which the valve-stems impinge whereby steam is admitted to and exhausted from the cylinders.

In witness whereof I have hereunto set my hand.

HENRY L. LIGHTNER.
